DESIGN FOR A FLUID CONTROL DEVICE

Ellwood G. Peterson, Chicago, Ill., assignor to
Hannifin Corporation, Chicago, Ill., a corpora-
tion of Illinois

Application December 6, 1947, Serial No. 143,007

Term of patent 14 years

(Cl. D78—1)

To all whom it may concern:

Be it known that I, Ellwood G. Peterson, a citizen of the United States, residing at Chicago, in the county of Cook and State of Illinois, have invented a new, original and ornamental Design for Fluid Control Device, reference being had to the accompanying drawing, forming a part thereof.

In said drawing:

Fig. 1 is an elevational view of one side of a fluid control device embodying my new design;

Fig. 2 is a similar elevation taken from a plane at right angles to that of Fig. 1;

Fig. 3 is a top plan view of the device taken from the plane 3—3 of Fig. 1 in the direction of the arrows; and

Fig. 4 is a bottom plan view of the device.

The characteristic features of my design for the fluid control device disclosed reside in the truncated or pyramidal cover or bonnet having the configuration shown.

I claim:

The ornamental design for a fluid control device, as shown and described.

ELLWOOD G. PETERSON.
